UNITED STATES PATENT OFFICE

WALTER T. HUFF, OF DAYTON, OHIO

CURTAIN STRETCHER

Application filed January 7, 1931. Serial No. 507,149.

This invention relates to curtain stretchers for stretching curtains of the lace or net variety after laundering.

It is customary after laundering lace or net curtains, to dry them under tension so that they will not materially take up or shrink, and in order that they may dry in a smooth, flat condition without wrinkles. The usual practice has been to mount the curtains while wet in a stretcher frame adjusted to predetermined size, in which the curtains are held by being engaged with hooks or pins along their margins. The shrinkage of the curtain in drying causes scallops or points to be formed on the margins of the curtain where engaged with the retaining hooks or pins of the stretcher frame, affording an unsightly appearance, and many times causing tearing of the curtain material.

It is not entirely new to stretch curtains by suspending them from a support with weights attached to the lower end of the curtain and to this end weight rods have been employed which are introduced through the marginal hem of the curtain at the top and bottom. However not all curtains are provided with terminal hems. Hence such method is not universally applicable.

In the present invention there are contemplated clamp members engageable with the opposite ends of the curtain to be stretched, one of these clamp elements at least being of sufficient weight to afford the necessary stretching effect when the curtain and its engaged clamp are suspended. The clamps, however, for the opposite ends of the curtain are of identical construction, and in the present embodiment comprise lengths of material bent reversely upon themselves to substantially parallelism to form a pair of clamp members of substantially "hair pin" shape and of sufficient length to extend entirely across the curtain to be engaged. U shaped spring clips are provided for holding the clamp arms in engagement with the curtain. Certain of these spring clips are reversely bent to form hangers by which the curtain and its engaged clamp members may be suspended.

The object of the invention is to simplify

the structure as well as the means and mode of operation of curtain stretching devices whereby they will not only be cheapened in construction but will be more efficient in use, capable of being easily and quickly applied, adapted to effect a uniform stretching action, and unlikely to get out of repair. 55

A further object of the invention is to provide stretching means which is applicable to curtains of all types whether provided with terminal hems, with fringe or otherwise shaped. 60

A further object of the invention is to provide stretching means which if desired can be introduced through the terminal hems as has been heretofore the practice, or which may be engaged exteriorly of such hemmed end. 65

A further object of the invention is to provide duo-functional spring clips which not only serve to hold the stretcher members in engagement with the curtain but also serve as hangers to suspend the curtain from an overhead support or line. 70

With the above primary and other incidental objects in view as will more fully appear in the specification, the invention consists of the features of construction, the parts and combinations thereof, and the mode of operation, or their equivalents, as hereinafter described and set forth in the claims. 75

Referring to the accompanying drawing wherein is shown the preferred but obviously not necessarily the only form of embodiment of the invention, Fig. 1 is a perspective view of a curtain to which has been applied the stretcher devices forming the subject matter hereof. Fig. 2 is a perspective view of one of the clamp members removed from the curtain. Figs. 3 and 4 are perspective views of spring clips for securing the clamp members in engagement with the curtain. Fig. 5 is a detail sectional view. 85

Like parts are indicated by similar characters of reference throughout the several views. 95

Referring to the drawing, 1 indicates the curtain or net, lace or other fabric to be stretched. Engageable with each end of the curtain 1 are clamp members 2—2, each of which comprises a continuous length of material bent upon 100

itself to substantially parallelism to form a "hair pin" form of clamp between the arms of which the end of the curtain is engageable. The material forming the clamp members 2 is preferably flat metal strips of sufficient weight to afford the necessary stretching effect. The clamp members 2 are plated or coated with some rust proof material or may be encased in suitable material such as celluloid, pyroxylin or the like which will protect the curtain against discoloration. The arms of the clamp member 2 are preferably slightly divergent when released from the curtain as is shown in Fig. 2 and are flexibly and 10 resiliently interconnected by the bight portion 3 which is preferably though not necessarily formed into a circular eye. The adjacent faces of the clamp arms are flat and hence do not mar the curtain to which the clamp is 15 attached. In applying the stretching device the end of the curtain is introduced between the clamp arms and is secured at one side by applying thereto a spring clip 4, the bight of which possesses sufficient tension to contract 20 the clamp arms upon the end of the curtain introduced therebetween. The curtain is then stretched transversely of the curtain or in line with the clamp member 2 and a second spring clip 4 is applied to the free ends of the arms 25 of the clamp 2 to contract the arms into clamping throughout the entire width of the curtain. To insure secure hold of the clamp upon the curtain, an additional clip 5 may be introduced at a mid length point of the clamp. 30 35 A similar clamp member 2 is applied in like manner to the opposite end of the curtain 1 and secured by the spring clips 5. The clips 4 employed at the ends of the upper clamp member have one side extended as at 6 and 40 reversely bent to form a hanger hook by which the curtain with its engaged stretcher clamps may be suspended from a line or overhead support. The bight of the clips 5 applied to the clamp element at the lower end of 45 the curtain is sufficiently deep to clear any fringe which may be carried by the curtain and extend beyond the clamp element 2. The curtain with the attached clamps being suspended from an overhead support, the weight 50 of the lower clamp element is sufficient to afford the necessary stretching action and maintain the curtain material tight or under tension while drying.

While the clamp members 2 are preferably 55 formed from flat bar stock as before mentioned, these clamp arms may be of other cross sectional contour, as for example semi-circular or even round. Likewise while the preferred method of application is exteriorly 60 of the curtain hems which are clamped between the arms 2, the elements 2 may be introduced through the terminal hems of the curtain as has heretofore been effected in which case the spring clips are unnecessary.

65 From the above description it will be ap-

parent that there is thus provided a device of the character described possessing the particular features of advantage before enumerated as desirable, but which obviously is susceptible of modification in its form, proportions, detail construction and arrangement of parts without departing from the principle involved or sacrificing any of its advantages. 70 While in order to comply with the statute the invention has been described in language more or less specific as to structural features, it is to be understood that the invention is not limited to the specific features shown, but that the means and construction herein disclosed comprise the preferred form of several modes of putting the invention into effect and the invention is therefore claimed in any of its forms or modifications within the legitimate and valid scope of the appended claims. 75 80 85

Having thus described my invention, I claim:

1. Means for stretching curtains and the like, comprising two U-shaped clamp members of sufficient length to extend transversely across the entire curtain, each end of which is to be engaged in one of the said clamps, one of the clamps being of sufficient weight to afford stretching strain to the curtain when suspended, and suspension means carried by the clamp within which the upper end of the curtain is engaged by which the curtain and engaged clamps may be supported. 90 95

2. A pair of elongated curtain clamps, each comprising a single length of material reversely bent upon itself substantially in parallelism and of sufficient length to extend transversely of a curtain and entirely thereacross, one end of which is engageable in each of the clamps, and hanger means carried by one of the clamps for engagement with a support to suspend the curtain therefrom with the other clamp supported entirely by the curtain which is subjected to stretching effect by the weight of said second clamp. 100 105 110

3. As an article of manufacture, a curtain clamp comprising a single length of material reversely bent upon itself substantially in parallelism and of sufficient length to extend transversely entirely across a curtain to be stretched, and means for holding the substantially parallel portions of the clamp in clamping engagement with a curtain introduced therebetween. 115

4. As an article of manufacture, a curtain clamp comprising a pair of members extending substantially in parallelism and of sufficient length to extend transversely entirely across the curtain to be stretched, one end of one of said members being fixedly attached to one end of the other member, the other ends of said members being free but resiliently urged toward each other, and means for hold- 120 125 130

ing the substantially parallel members of the clamp in clamping engagement with a curtain introduced therebetween.

In testimony whereof, I have hereunto set
5 my hand this 31st day of December A. D.
1930.

WALTER T. HUFF.
